UNITED STATES PATENT OFFICE.

FRED H. REAM, OF KANSAS CITY, MISSOURI.

RADIATOR-SHIELD FOR AUTOMOBILES.

1,368,453.

Specification of Letters Patent. Patented Feb. 15, 1921.

Application filed August 9, 1919. Serial No. 316,320.

To all whom it may concern:

Be it known that I, FRED H. REAM, a citizen of the United States, and residing in Kansas City, in the county of Jackson 5 and State of Missouri, have invented a new and useful Radiator-Shield for Automobiles, of which the following is a specification.

My invention relates to radiator shields for automobiles and particularly to a device 10 of this character which is used to shield and protect the radiator from cold air to prevent freezing of the water therein.

The object of my invention is to provide a shield consisting of a plurality of rotatable 15 shutters which may be attached on the cellular filling of the radiator and a reciprocating bar provided with a plurality of cams having facility for alternately reciprocating the shutters.

I attain this object by means of the mechanism illustrated in the accompanying drawing in which—Figure 1, is a sheet metal blank of one of the shutters; Fig. 2, is a side elevation of the shield, the side plate being 20 removed to disclose the crank arms on the shutters and the reciprocating bar for reciprocating the shutters; Fig. 3, is a rear elevation of a fragment of the device, and showing the springs for holding the shutters 25 normally closed; Fig. 4, is a side elevation of the shield, partly sectioned, to show the means of attaching the device to the radiator front; and Fig. 5, is a front elevation of the device, partly broken away, to 30 disclose the parts.

The numeral 1, is an oblong plate of sheet metal having ears 2 and 3, at its opposite ends. The ear 2, includes a neck portion 4, and a head portion 5, the lower portion of 40 the latter is cut away and the cut away portion 6, is bent to form a guide 7, and thereby forming a crank arm 8, the latter with the neck portion 4, forming a bell crank. The ears 2 and 3 are bent and each is provided with a pivot pin 9, which is extended 45 outwardly in the same plane. The upper margin of the plate is bent on the dotted line 10, to form a concaved channel 11, and the lower margin of the plate is formed back on the dotted line 12, to form a flange 13. The plate thus formed up produces a sheet metal 50 shutter 14. A frame 15, is provided and adapted for receiving the shutters 14, and comprises heads 16 and 17, side plates 18 and 19, and front plates 20 and 21. The heads 16 and 17, are provided with clamp-

ing bolts 22, which are adapted for passing through the openings in the cellular filling of the radiator. Side plates 18 and 19, and likewise front plates 20 and 21 are connected 60 between the heads. A reciprocating bar 23, is disposed vertically adjacent the inner side of the side plate 19, and is provided adjacent its upper and lower ends with outwardly projecting pins 24, which are extended 65 through slotted apertures 25, in the upper and lower portions of the side plate 19, and which are elongated in degree and adapted for limiting the vertical movements of the reciprocating bar 23. The pivot pins 9, on 70 the shutters 14, are loosely pivoted in the side plates 19 and 18, in such a manner that the guide 7, on the crank arm 8, shall receive loosely the reciprocating bar 23, edge-wise. The lower margin of the upper head 75 16, is formed up inwardly to provide a flange 26, which is adapted to enter the concaved channel 11, in the upper margin of the top shutter, and the upper margin of the lower head 17, is formed up outwardly and 80 concaved to form a channel similar to channel 11, in the shutters. Coiled springs 27, are mounted on the pivots 9, on the ears 3, and connected between the frame and the shutter, in such a manner that they shall 85 hold the shutters normally closed. The reciprocating bar 23, is preferably made of a flat bar of metal, and which is cut away at its front edge to form spaced apart projecting cams 28, the contour of the cams, 90 from their upper parts downward, a downwardly beveled edge 29, an inwardly curved edge 30, and a short beveled edge 31, then a vertical edge 32, which is extended downward a suitable distance adapted for holding 95 the shutter engaged thereby, wide open during a time interval necessary to allow the cams below to open wide the shutters engaged thereby, as will be further explained. The reciprocating bar is cut away inwardly 100 in curved line between each cam, thereby spacing the cams apart, the spacing distance being arranged to allow the uppermost cam to open wide the shutter engaged thereby, before the next lower cam shall rotate the 105 shutter engaged by it, and so on thereafter in the series of cams. The timed edge 32, differs from the timed curved edge 33; the former, in the case of the uppermost cam, must hold the shutter engaged by it open 110 during the upward movement of the reciprocating bar, or, until all the shutters are

wide open and, in the case of the lower cams, the same condition would apply. A flexible wire rod 34, is attached on the lower portion of the back edge of the reciprocating bar, 5 and its free end is passed through an upper opening in the cellular filling of the radiator, and extended inwardly to the automobile, where the rod is provided with a handle 35, for conveniently operating the shutters. 10 My invention is attached to the radiator front by bolts 22, which are passed through openings in the cellular filling of the radiator. The shutters are held normally closed by the reaction of the springs 27. To open 15 wide all the shutters, a pulling pressure is applied to the rod 34, thereby the reciprocating bar 23, is forced upward a distance limited by the pins 24 reaching the upper ends of the slots 25. In rising, the outer 20 edge of the reciprocating bar slides through the guides 7, on crank arms 8, the crank arm on the uppermost shutter engaging the uppermost cam and sliding down the beveled edge 29, thereon, and on the curved 25 edge 30, and beveled edge 31, to and on the vertical edge 32, when the shutter will be opened wide to occupy a horizontal position. The reciprocating bar continuing to rise the succeeding cams on the bar will 30 similarly engage the other crank arms and rotate their respective shutters, in turn, one after the other. The timing space between the respective cams on the bar is arranged to allow the uppermost shutter to open wide 35 before the next lower shutter shall start opening, and so on down through the series of shutters. The timing distance of the vertical edge 32, of the uppermost cam, is arranged to hold the shutter wide open until 40 all shutters are opened wide, and each of the cams are similarly provided with timed vertical edges 32, adapted for holding their respective shutters wide open until all shutters are opened wide. To close the shutters 45 a pushing pressure is applied to the rod 34, when the reciprocating bar will be forced down, when the tension of the springs 27,

will rotate the shutters backward to normal closed position, the guides 7, on the crank arms 8, traveling in reverse direction on and over the edges of the cams, the flange 13, on the lowermost shutter entering the channel 11, in the lower head 17, and the channel 11, on the shutter receiving the flange 13, on the next above shutter, the channel on the latter 55 receiving the flange of the uppermost shutter, and the channel of the latter receiving the flange 26, on the upper head 18; thereby the shutters are substantially interlocked in closed position. 60

It is obvious that the arrangement of the cams on the reciprocating bar, together with the timing thereof to alternately perform their functions, is a provision whereby all the shutters in a series of shutters may be 65 opened wide and closed, one or more opened and closed, and one or more opened wide and one or more partially opened, so that cold air, rain and snow, may be entirely excluded from the radiator front to prevent 70 freezing of the water therein, and the admission of air to the radiator regulated.

Having described my invention what I claim is—

A radiator shield for automobiles, consisting of a frame, a series of interlocking shutters pivoting in said frame and provided with crank arms having guides, tension springs connected between said frame and said shutters and adapted for holding 75 the shutters normally closed, and a bar slidably mounted on said frame and provided with a series of spaced cam projections, the spaces between the cams successively increasing in distance from the top to the bottom of the bar whereby said cams are 80 adapted to successively engage the guides upon the crank arms for progressively opening the shutters. 85

Kansas City, Missouri, July 31st, 1919.
